UNITED STATES PATENT OFFICE

BENZION WOLF, OF CHICAGO, ILLINOIS

GARTER

Application filed March 31, 1930. Serial No. 440,194.

This invention relates to garters generally and particularly to anatomic garters. More specifically, the invention relates to improvements in garters of the type which are shown and disclosed in my Patents Nos. 1,737,067; 1,772,274; and 1,781,673.

The primary object of the present invention is to provide a new and improved garter which is provided with an ankle encircling portion and upwardly extending converging strips or supports which prevent relative movement of the strips or supports when in position on the leg of a wearer.

Another object is to provide an anatomic garter having a pair of upwardly extending sock stays whereby the sock stays are prevented from being thrown out of position during wear.

Numerous other objects and advantages will be apparent throughout the progress of the following specification.

The invention comprises in general a band or web which is adapted to encircle the ankle of a wearer and a pair of upwardly extending leg portions which are connected to the ankle band or web. The ankle band is provided with a slidable buckle as set forth in the aforesaid copending application Serial No. 434,571 so as to make the garters adaptable to various sizes. The vertical leg portions are each provided with a pocket into which a reinforcing stay is inserted. The pocket may be closed by means of a slidable buckle as mentioned in the last named copending application, or the pockets may be stitched across the top, if desired. The upwardly extending leg portions may be connected together as shown in the various figures and one or more keepers having cooperation with one or more clasps are provided for fastening the socks in position.

The accompanying drawing illustrates a selected embodiment of the invention and the views therein are as follows:

Fig. 1 is a detail view of the improved garter arranged on the leg of a wearer and supporting a sock.

Fig. 2 is a detail longitudinal sectional view of a modified form of garter shown in Fig. 5, and applied to a sock.

Fig. 3 is a detail plan view of the garter shown in Fig. 1.

Fig. 4 is a detail elevation of a modified form of garter.

Fig. 5 is a detail perspective view showing a modified form of garter shown in Fig. 2.

Referring to the drawing, 1 designates a band or anklet portion which is adapted to fit around the ankle of a wearer. Vertical members or strips 2 and 3, Fig. 1, are fastened to the ankle portion or band in any convenient manner such as by stitching 4. The ankle band may be made of any kind of material desired such as ordinary webbing or elastic. The vertical members or strips 2 and 3 may also be made of any kind of fabric desired although it is preferable that these be made of some material which is non-elastic. The vertical strips 2 and 3 are preferably made of two plys of fabric 5 and 6, Fig. 2, and these two plys of fabric are preferably stitched along the edge 7 to provide a pocket 8 into which a reinforcing member or stay 9 is received. After the stay is inserted in the pocket, the pocket may be closed by means of a buckle 10, Fig. 2, or the pocket may be stitched at a point designated at 11, Fig. 2, for preventing the stay from coming out of the pocket. It may be preferred, however, that the buckle 10 be employed as the stay can be removed and the entire garter washed. The fabric 5 may have an extension 12 to which a clasp 13 is fastened. The clasp 13 cooperates with a button 14 on a keeper 15. This keeper is herein shown as being permanently fastened to the outer fabric 6 but it may be used in any other desired manner such as set forth in the aforesaid last mentioned copending application. The garter is arranged next to the leg of a wearer and is arranged inside of a sock 16. The extension 12 extends above the top of the sock 16, is turned over and engages the button 14 and the keeper 15, as clearly shown in Fig. 2.

The garters shown in Figs. 1 and 3 have the extensions 12 on each of the vertical members 2 and 3 positioned so that the extensions are arranged in the form of an inverted V. The extensions are connected together as indicated at 17, Fig. 3. A cross-band 18 con-

nects the vertical members 2 and 3 as clearly shown in Fig. 3. The keeper 15 with its attached button 14 is mounted on the cross-band 18. In this construction the clasp 13 cooperates with the keeper to hold the sock 16 in position. By having two upwardly extending vertical members connected together, the vertical members will always maintain their proper position. In cases where only one vertical member is used, it is possible that it will shift or bow inside of the sock causing a bulky appearance, or it may bend-over and prevent the sock from being properly supported. In Fig. 4 the cross-band 18 is provided for holding the two members 2 and 3 together. The vertical members are spaced apart and not joining or converging in the manner shown in Fig. 3. In employing the construction shown in Fig. 4, two keepers 15 with their cooperating buttons 14 are provided and a clasp 13 is fixed to each of the two extensions 12. This latter construction gives practically the same support as the construction shown in Figs. 1 and 3, but has two 25 clasps and keepers whereby the construction shown in Figs. 1 and 3 has but one clasp and keeper.

The substantially V-shaped positioning of the two vertical leg members causes one leg member to reinforce the other and prevent either of the vertical members from sliding, shifting, or turning when arranged in position. It is to be understood, of course, that the stays are flexible enough to permit the vertical members with their cooperating stays to conform with the shape of the leg as shown in Fig. 1, but the present construction prevents the stays from springing sideways or bowing outwardly as may be the case if only one vertical stay were used.

It will be noticed that in Figs. 1 to 4 the lower edges of the vertical members 2 and 3 are spaced relatively far apart with their upper edges connected or spaced relatively close together. This construction, however, can be inverted as shown in Fig. 5. In this latter figure the bottom edges of the vertical members are stitched to the ankle encircling portion relatively close together. The vertical members incline outwardly and are connected near their upper edges by the cross-band 18. In this latter embodiment the band 18 is relatively longer than the bands 18 shown in Figs. 3 and 4. However, the clasps fasten the sock 16 in position in exactly the same manner as those shown in Figs. 1 to 4. The construction shown in Fig. 5 holds the vertical member 2 in position relative to the other vertical member 3 and prevents either vertical member from bowing or shifting.

The free end 19 of the outer strip 6 may have a clip or fastener 20 fixed thereto, as clearly shown in the drawing, for preventing the end of the strip from unraveling.

65 The invention provides a garter which is

comfortable to wear, which does not bind the wearer or strangle the circulation, which is form-fitting, and which smoothly and securely holds a sock in proper position. The garter is simple in construction, can be readily 70 and economically manufactured, is washable, and is comfortable to wear.

I am aware that the vertical leg members may extend upwardly at any angle or they may be curved. In other words, the vertical 75 leg members form an arch which may be in the form shown in Figs. 1 to 4, or inverted as shown in Fig. 5. The term "arch" as used in the claims is to be construed broadly and includes any kind or shape of arch whether it be rounded, V-shaped, or any other shape desired. Instead of having two or more leg members it is to be understood that only one member may be used and this member, folded over, bent, or returned to conform with an 80 arch or similar shaped member.

Changes may be made in the form, construction, and arrangement of the various parts without departing from the spirit of the invention or sacrificing any of its advantages, and the right is hereby reserved to make all 90 such changes as fairly fall within the scope of the following claims.

The invention is hereby claimed as follows:

1. A garter comprising a band adapted to 95 encircle the ankle of a wearer, a plurality of upwardly extending members fastened to said band, said members constructed and arranged in the shape of a V, a strip or band connecting said members together near their upper ends, a keeper fixed to said garter, a clasp cooperating with the keeper, and reinforcing stays arranged in said members.

2. A garter comprising a band adapted to 100 encircle the ankle of a wearer, a plurality of upwardly extending members fastened to said band, a strip or band connecting said members together near their upper ends, extensions on said members and fastened together, and means for fastening a sock to said fastened 105 extensions.

3. A garter comprising a band adapted to 110 encircle the ankle of a wearer, a plurality of upwardly extending members fastened to said band, a strip or band connecting said members together near their upper ends, extensions on said members and fastened together, a single clasp fastened to said fastened extensions, and a single keeper fastened to said 115 strip or band to cooperate with said clasp.

4. A garter comprising a band adapted to 120 encircle the ankle of a wearer, flat fabric strips fastened to said band at their lower ends and extending upwardly and obliquely therefrom, means connecting said members together toward their upper ends, a keeper, and a clasp at an end opposite from the band and adapted for engagement with said keeper.

5. A garter adapted to be worn under a 125 sock comprising an ankle encircling member,

leg members extending upwardly from said first named member and fastened thereto, said members inclining toward each other, means fastening the leg members together near their upper ends, a clasp connected to at least one of said leg members, and a keeper cooperating with said clasp.

In witness whereof, I have hereunto subscribed my name.

10 BENZION WOLF.
